UNITED STATES PATENT OFFICE.

PATRICK H. BRENNAN, OF SYRACUSE, NEW YORK.

CARBURETER.

No. 821,081.

Specification of Letters Patent.

Patented May 22, 1906.

Application filed December 12, 1904. Serial No. 236,555.

To all whom it may concern:

Be it known that I, PATRICK H. BRENNAN, a citizen of the United States, residing at Syracuse, in the county of Onondaga and State of New York, have invented certain new and useful Improvements in Carbureters; and I do hereby declare the following to be a full, clear, and exact description of the invention, such as will enable others skilled in the art to which it appertains to make and use the same.

My invention relates to carbureters for explosive-engines; and it consists in a new construction and arrangement of parts by which the liquid fuel is purified and filtered, its flow regulated, and the admission of the air regulated and controlled so as to be proportioned to the gasolene or other liquid fuel.

A practical and desirable embodiment of my invention is represented in the accompanying drawings, in which the reference-numerals of the specification indicate similar parts in all the figures.

Figure I is a front elevation of a suitable form of device, showing my invention. Fig. II is a vertical section parallel to the elevation of Fig. I. Fig. III is a top plan. Fig. IV is a plan with certain parts removed. Fig. V is taken at a right angle to Fig. III and is practically an elevation to illustrate the position and operation of the air-valve.

In the figures, 1 indicates the shell, formed in a single piece and provided with float-chamber 2, inlet-channel 3, and mixing-chamber 4. In the float-chamber is a guide 6 for the stem 7 of float 8, carrying above the needle-valve 10, fitting the elongated feed-channel 11 in a column 12 in the filtering top or filter 13, threaded to fit the upper margin of the float-chamber and to form a cover therefor. This filter is provided with an inlet 15 for the liquid fuel supplied through pipe 14 and a blow-off 16, to which is fitted petcock 17 for drawing off refuse, foreign matter, &c. In the upper portion of its chamber 20 is arranged a fine-meshed strainer 21, fitting around and below the upper end of the column formed to receive it. A threaded cover 22, provided with projection 23 for wrench, closes the filtering-chamber.

25 is a vent fitted with spring-valve 26, inclosed in tube or case 27, so as to protect parts from dust, &c., which would tend to clog the valve.

55 The gasolene enters the bottom of the filter and passes up through the strainer or screen

by which the water, oil, grease, dirt, &c., are retained and can be drawn off through the petcock. The gasolene flows down through the feed-channel and, being filtered, a practically perfect operation of the float and carbureter is insured.

From the bottom of the float-chamber the gasolene passes through inlet-channel 3 to mixing-chamber 4, where its admission is controlled by controlling-valve 32, whose valve-stem 34, having one or more flattened portions, fits seat 35 in the inlet, and whose valve-rod 36 is threaded to fit within the tubular stem 40 of the throttle-valve 41 and carries on its outer end arm 37, to which is connected lever 38, arranged conveniently to the hand of the operator, whereby the controlling-valve may be adjusted up or down with reference to its seat to control the amount of gasolene admitted. This valve is provided with the ribbed conical portion to break up and atomize the indrawn liquid fuel and with a slot on the outer end of its rod to permit easy adjustment by the screw-driver.

Throttle-valve 41 is provided with port 42 and is adapted to be turned by its arm 44 and lever 40 to regulate the flow of the explosive mixture through vapor-outlet 43 into the cylinder. This arm 44 is provided with an extension or tail 45 to engage with stop-lugs 46 46 on the shell to limit the throw of the valve and to notify the operator that the limit has been reached. This arm is also provided with cross-piece 48, curved, as here shown, or of other suitable shape, carrying two stops 49 49 to engage with arm 37 on controlling-valve rod and limit the movement of said controlling or mixing valve to avoid excessive movement of the controlling-valve and the admission of an amount of liquid fuel decidedly too large or too small. The mixed vapor is delivered through port 42 and outlet 43 in extension 75, to which pipe is attached.

Journaled in bearings adjacent to air-inlet 50 is the air-valve 51, which is adapted to regulate the admission of air according to different altitudes and size and speed of engine. This valve may desirably be of shutter form and provided with crank 53, pivotally connected by connection 54 and collar 56 to sliding rod 57, sliding in ears 58, which may be cast integral on exterior of shell. This connection may be adjusted on said sliding rod by said collar, provided with usual clamping-bolt, to adjust the position of

the air-valve for different altitudes, the higher the wider open, or for different sizes of engines, the larger the wider open, giving quite a wide range of utility. This air-valve is held normally open by a suitable spring 60 and is closed more or less simultaneously with the throttle-valve by eccentric cam 62 on throttle-valve arm engaging with upper end of sliding rod and forcing it down. It is desirable that the air-valve and throttle-valve operate simultaneously, because, for instance, when running slow a part of the air should be cut off or the mixture would be too weak.

I do not wish to limit myself strictly to the structure here shown, as changes may be made in the form and arrangement of the various parts without departing from the spirit and scope of my invention.

Having thus described my invention, what I claim as new, and desire to secure by Letters Patent, is—

1. In a carbureter for a gas-engine, the combination with a suitable shell inclosing a mixing-chamber having gasolene and air inlets in its lower portion and a vapor-outlet in its upper portion, of a shutter air-valve journaled across the air-inlet, an external crank on said air-valve, a sliding rod arranged in bearings on the shell, a connection between said rod and said crank, a spring engaging with the rod to hold the valve open, a throttle-valve in the mixing-chamber controlling the vapor-outlet, an outwardly-extending stem on the throttle-valve and an eccentric cam connected to said stem and engaging with the sliding rod to operate said valves simultaneously.

2. In a carbureter for a gas-engine, a mixing-chamber shell provided with an inlet-channel and an air-inlet in its lower portion and a vapor-outlet in its upper portion, and in combination therewith a throttle-valve arranged within the mixing-chamber and having a port to register with the vapor-outlet, a tubular stem on the throttle-valve outwardly extending through the top of the chamber, an arm secured to the outer end of said stem, a tail on said arm, stop-lugs on the shell to engage with said tail and limit the movement of the throttle-valve, stops on said arm, a controlling-valve arranged in the mixing-chamber, to control the admission of the gasolene through the inlet, a valve-rod on the throttle-valve extending outwardly through said tubular stem, said rod being threaded to engage with the interior of said stem, a second arm secured to the outer end of said valve-rod and arranged between the stops on the first arm.

3. In a carbureter for a gas-engine, a mixing-chamber shell provided with an inlet-channel and an air-inlet in its lower portion and a vapor-outlet in its upper portion, and in combination therewith an air-valve jour-

naled in the air-inlet to control the supply of air, an external crank on the air-valve, a vertical sliding rod fitted to ears on the exterior of the shell, a collar adjustably fitted to said rod, a spiral spring arranged around the rod between the collar and one ear to hold the rod up and the valve open, a connection connecting said crank and collar, a throttle-valve fitted to the enlarged upper portion of the mixing-chamber and having a port to register with the vapor-outlet, a tubular stem on the throttle-valve outwardly extending through the top of the chamber, an arm secured to the outer end of said stem, an eccentric cam on said arm to engage with said sliding rod and force it downwardly to close the air-valve, more or less, simultaneously with the throttle-valve, a controlling-valve arranged in the mixing-chamber to control the admission of gasolene, a valve-rod on the controlling-valve extending outwardly through said tubular stem, said rod being threaded to engage with the interior of said stem, and a second arm secured to the outer end of said valve-rod.

4. In a carbureter for a gas-engine, a mixing-chamber shell provided with an inlet-channel and an air-inlet in its lower portion and a vapor-outlet in its upper portion, and in combination an air-valve to control the supply of air through the air-inlet, a throttle-valve fitted to the enlarged upper portion of the mixing-chamber and having a port to register with the vapor-outlet, a tubular stem on the throttle-valve outwardly extending through the top of the chamber, an arm secured to the outer end of said stem, a lever connected to said arm, a tail on said arm, stop-lugs on the shell to engage with said tail and limit the movement of the throttle-valve, a curved cross-piece on said arm having an upwardly-extending stop at each end, a connection between said arm and the air-valve to operate the air-valve simultaneously with the throttle-valve, a controlling-valve longitudinally arranged in the mixing-chamber and having a stem fitting a seat in the upper end of the inlet, a ribbed conical portion immediately above said stem and a valve-rod extending outwardly through said tubular stem, said rod being threaded to engage with the interior of said stem and a second arm secured to the outer end of said valve-rod and arranged between the stops on the first arm, substantially as described and shown.

5. In a carbureter for a gas-engine, the combination with a mixing-chamber shell having gasolene and air inlets and a vapor-outlet, a valve for the air-inlet, a sliding rod connected to said valve whereby the valve is controlled, a throttle-valve for the outlet, a cam on the throttle-valve engaging with said rod whereby the valves are closed simultaneously, and a controlling-valve for the oil-inlet.

6. In a carbureter for a gas-engine, the

combination with a mixing-chamber shell having oil and air inlets and a vapor-outlet, of an air-valve controlling the air-inlet, a rod fitted to slide in external bearings on the shell and connected to the air-valve, a throttle-valve for the vapor-outlet, an eccentric cam on the throttle-valve engaging with said rod, a lever connected to the throttle-valve whereby said valves are closed simultaneously and a plunger-valve for the oil-inlet.

7. In a carbureter for a gas-engine, the combination with a mixing-chamber shell having oil and air inlets and a vapor-outlet, of an air-valve journaled across the air-inlet, a rod fitted to slide in bearings and connected to said valve, a spring tending to open said valve, a throttle-valve for the outlet, an eccentric cam connected to the throttle-valve and engaging with said rod, whereby the valves are operated simultaneously; and a plunger-valve for the oil-inlet.

8. In a carbureter for a gas-engine, a mixing-chamber shell provided with an inlet-channel and an air-inlet in its lower portion and a vapor-outlet in its upper portion, and in combination therewith a shutter-valve journaled in the air-inlet to control the supply of air, an external crank on the air-valve, a vertical sliding rod fitted to ears on the exterior of the shell, a collar adjustably fitted to said rod, a spring arranged around the rod between the collar and one ear to hold the rod up and the valve open, a connection connecting said crank and collar, a throttle-valve fit-

ted to the enlarged upper portion of the mixing-chamber and having a port to register with the vapor-outlet, a tubular stem on the throttle-valve outwardly extending through the top of the chamber, an arm secured to the outer end of said stem, a lever connected to 35 said arm, an extension or tail on said arm, stop-lugs on the shell to engage with said extension or tail and limit the movement of the throttle-valve, a curved cross-piece on said arm having an upwardly-extending stop at 40 each end, a cam on said arm to engage with said sliding rod, and force it downwardly to close the air-valve, more or less, simultaneously with the throttle-valve, a controlling-valve longitudinally arranged in the mixing-chamber, and having a stem fitting a seat in 45 the upper end of the inlet, a ribbed conical portion immediately above said stem and a valve-rod extending outwardly through said tubular stem, said rod being threaded to engage with the interior of said stem and having a slot on its outer end, a second arm secured to the outer end of said valve-rod and arranged between the stops on the first arm, and a lever attached to said second arm, substantially as described and shown.

In testimony whereof I affix my signature in presence of two witnesses.

PATRICK H. BRENNAN.
